UNITED STATES PATENT OFFICE.

EDWARD HINCK, OF CROSS KEYS, NEW JERSEY.

DESIGN FOR AN ELECTRIC-LIGHT FIXTURE.

Application filed June 2, 1925. Serial No. 13,638. Term of patent 3½ years.

To all whom it may concern:

Be it known that I, EDWARD HINCK, a citizen of the United States, residing in Cross Keys, in the county of Camden and State of New Jersey, have invented a certain new, original, and ornamental Design for Electric-Light Fixtures, of which the following is a specification, reference being

had to the accompanying drawing, forming part thereof.

The figure is a perspective view of an electric light fixture, showing my new design.

I claim:

The ornamental design for an electric light fixture, as shown.

EDWARD HINCK.
